(57) **CLAIM**

The ornamental design for a red dot sight, as shown and described.

DESCRIPTION

FIG. 1 is a front view of a red dot sight, showing our new design;

FIG. 2 is a back view of the red dot sight;

FIG. 3 is a left view of the red dot sight;

FIG. 4 is a right view of the red dot sight;

FIG. 5 is bottom view thereof;

FIG. 6 is a top view thereof;

FIG. 7 is a front, top, left perspective view thereof;

FIG. 8 is a rear, top, right perspective view thereof;

FIG. 9 is a front view of the red dot sight thereof with the covers in an open state;

FIG. 10 is a rear view of the red dot sight thereof with the covers in an open state;

FIG. 11 is a left view of the red dot sight thereof with the covers in an open state;

FIG. 12 is a right view of the red dot sight thereof with the covers in an open state;

FIG. 13 is a bottom view of the red dot sight thereof with the covers in an open state;

FIG. 14 is a top view of the red dot sight thereof with the covers in an open state;

FIG. 15 is a front, top, left perspective view of the red dot sight thereof with the covers in an open state; and,

FIG. 16 is a rear, top right perspective view of the red dot sight thereof with the covers in an open state.

The portions shown in dotted lines do not form any part of the design and are included for illustrative purposes only. The shadings shown in the drawings merely illustrate a transparent characteristic of the surface, while the shadings themselves form no part of the claimed design.
